PRINTING MECHANISM FOR ACCOUNTING MACHINES

Fred M. Carrell, Yonkers, N. Y., assignor, by
mesne assignments, to International Business
Machines Corporation, New York, N. Y., a cor-
poration of New York

Application August 17, 1928, Serial No. 300,254

24 Claims. (Cl. 101—93)

This invention relates to printing mechanisms for accounting, tabulating machines or the like and is primarily directed to printing additional matter on a record sheet by auxiliary impression members, such as stencilled plates, matrices, printing plates, or the like, which are selectively and conditionally positioned at definite cycles of machine operation.

The present improvements find particular application to machines provided with entry receiving and printing devices which cause to be printed upon a continuous work sheet account data, such as, for example, groups of items with a related total. Printing of the items may be controlled by record cards, the perforations of which represent the items and other classification data. Such printed accounts may constitute bills or statements and heretofore, contained no identification data, such as account names, addresses, etc. The present invention provides for selectively feeding to the printing mechanism impression members carrying the proper identification data whereby each account as printed is suitably identified. Preferably, the impression members are compared with the item entry controlling devices so that printing of the wrong identification data will be effectively prevented.

It is then a broad object of the present invention to provide for printing identification or other data by presenting auxiliary impression members to an impression receiving element, such as a record strip.

It is a still further object to provide means whereby the impression members are presented to the record strip as an incident to certain machine operations.

More specifically it is an object of the present invention to identify printed accounts comprising a series of items with a related total by presenting a related impression member to a record strip carrying such printed accounts.

It is a still further object to analyze each impression member to determine whether it is related to the account it is to identify and to cause stoppage of the machine upon failure to properly compare.

Further objects of the invention comprise the provision of electrically controlled analyzing and machine controlling devices which automatically inhibit the presentation of a wrong impression member to the record strip upon lack of identify between the impression member and the item entry controlling devices.

To these and other ends the invention consists in the novel features of construction, arrange-

ment of parts, and combination of elements hereinafter described, and more particularly set forth in the claims.

In the drawings:

Fig. 1 is an end view of the illustrative machine embodying the present improvements.

Fig. 2 is a front view of the upper part of the machine shown in Fig. 1.

Fig. 3 is a cross sectional view of the identifying plate feeding, analyzing and printing mechanisms constructed according to the present invention.

Fig. 4 is a top plan view of the mechanism shown in Fig. 3 and is taken on the line 4—4 of Fig. 3.

Fig. 5 is a cross sectional view and shows in detail the construction of the clutch mechanism and associated electrical control devices.

Fig. 6 is a detail view taken on the line 6—6 of Fig. 5.

Fig. 7 is a sectional view of the identifying plate analyzing and comparing devices showing their relationship to a printing plate.

Fig. 8 is a detail of the brush contact devices taken on the line 8—8 of Fig. 7.

Fig. 9 is a diagrammatic representation of the electrical control system which may be employed in connection with the present improvements.

Fig. 10 is a plan view of a printing plate provided with identifying and classification characters.

Fig. 11 is a representation of a part of a record strip printed according to the present improvements.

Referring to Fig. 11 it will be observed that the present invention contemplates effecting the identification of data comprising, for example, a series of items with a total thereof. These data may comprise accounts of various persons and are preferably placed upon pre-printed work forms which constitute bills or statements of accounts rendered. Any suitable entry receiving device may be employed for printing the variable account data upon the work forms.

The present improvements are illustrated herein in connection with a tabulating machine of the form fully shown and described in the patent to C. D. Lake, No. 1,379,268 dated May 24, 1921. The particular type of machine does not enter into the present invention as any other form of entry receiving device would serve the purpose of explanation and embodiment equally as well.

Referring now to Fig. 9, a stack of cards which represent the items of the various accounts are indicated at 10 and are adapted to be advanced by a picker 11 operated by an arm 12 and drawn into cooperative relationship with a pair of feed-

105

110

ing rollers 13. The picker feeds one card at a time to the rollers 13 which advance it during one machine cycle to the upper or control brushes 14 and during a later machine cycle to the lower or adding brushes 15. The rollers and feed mechanism are driven from a shaft 16 rotated by the usual tabulating motor and a gear train indicated generally by reference character 17. As the perforated cards are fed to the adding brushes the 10 index points are sensed in the usual manner in order that the printing type 18 (Fig. 2) may be differentially controlled. Item and total printing operations are effected by impelling the selected type against the usual roller platen 19, im- 16 pressions being effected upon the record strip 20 by the customary inking ribbon. During item listing operations a shaft 21 (Fig. 1) is operated to drive the various mechanisms.

It should further be explained that each record 20 card carries a group of perforations representing a particular classification or group number. These perforations are sensed by brushes 14 and 15 but when a card having a new group number is presented to the brushes 14, item printing is 25 terminated and the control mechanism more fully illustrated in the patent to C. D. Lake, No. 1,600,413, dated September 21, 1926 conditions the machine for a total taking operation. During this operation shaft 21 is idle but a total taking 30 shaft 22 (Fig. 1) is driven to operate various mechanisms as an incident to total printing operations.

Any suitable paper strip spacing mechanism may be provided for effecting paper spacing operations such as, for example, the type disclosed in 35 the co-pending application of F. M. Carroll, Serial No. 287,549, filed June 22, 1928 to which reference may be had for further details of construction and operation. The paper strip 20 (Fig. 1) is 40 drawn from a supply roll, thence passes about a tensioned roller 23, a fixed roller 24, around the platen 19 and thence between pairs of feeding rollers 24a and 24b (Fig. 3). Feeding rollers 24a are driven intermittently as an incident to 45 item printing operations to suitably space the items as shown in Fig. 11. The paper strip 20 is, however, preferably given a greater spacing before and after total printing operations in order that the total be printed on some predetermined 50 line and to provide space to accommodate the variable identifying data 25 exemplified herewith as account names. Such printed matter identifies the data which follows below, and which preferably comprises a series of items with 55 a related total.

In the present instance the identifying data is printed by a member 26 (Fig. 10) which may be a printing plate of any suitable material but is exemplified herewith as a plate carrying sten- 60 cilled data for printing names of accounts, and, in addition, preferably carries perforations 27 representing an arbitrary account number.

For the purpose of successively feeding the printing plates 26 which are initially stacked as 65 shown in Fig. 3, a bar 28 (Figs. 2 and 3) slidably mounted in a frame 29 is provided. The bar 28 carries spring urged picker members 30, a pair of which engage the front and rear edges of the lowermost plate 26 to positively feed it from the 70 bottom of the stack when said bar 28 is moved in one direction. Suitable spring pressed members or other means may be provided to hold the plate fed in this manner impositively on the upper surface of frame 29 while the bar 28 and picker 75 members 30 are returned to normal position. It

will be obvious that when the next plate at the bottom of the stack is fed, the plate previously fed will be moved to the right (as viewed in Fig. 3) so that three cycles of operation are required to move a plate 26 from the stack to a gripper to be presently described.

Under certain conditions bar 28 is automatically reciprocated as an incident to a total taking operation by the following mechanism: Bar 28 carries a pin 31 engaging a bifurcation of a lever 32 at an end distant from its connection to a rock shaft 33. Shaft 33 has secured to it an arm 34 having a pin 35 engaging a closed slot 36 of a link 37 articulated to a spring urged bell crank 38 whose roller 39 cooperates with a cam 40 attached to a sleeve 130 which, under certain conditions is clutched to a shaft 41 driven during each total taking operation. Shaft 41 (Fig. 1) carries a bevel gear 42 meshing with a similar bevel gear 43 on a connecting shaft 44, the latter being driven by shaft 22 by a similar pair of intermeshing bevel gears 45.

Secured to a shaft 46 (Fig. 4) journaled in the side frames 47 of the attachment is an arm 48 biased by a spring 49 (Fig. 3) so that a roller carried thereby engages a profile cam 50 secured to sleeve 130. Pinned to shaft 46 is a pair of spaced arms 52 and 53 (Fig. 4) which are provided at their ends with journal collars 54 which support a slidably mounted shaft 55. Splined to the shaft 55 by a key 56 is a yoke shaped plate gripper frame 57 the side arms of which carry their respective gripper arms 58 pivoted at 59 and urged towards each other by a connecting spring 60.

Pinned to shaft 55 is a pair of mushroom-shaped cams 61 engaging the extensions 62 of the respective arms 58, it being clear that as shaft 55 is shifted the free ends of arm 58 will be moved away or towards each other, and that the angular position of frame 57 is dependent 110 on the turning of shaft 55, and furthermore, the various positions of gripper arms 58 and frame 57 may be assumed independently of each other to perform the necessary operations.

Since the shaft 46 is rocked by cam 50 it will 120 also be clear that the position of shaft 46 also controls the position of the arms 52 and 53 and the parts carried thereby.

In order to provide for the necessary positioning of arms 58 by shifting shaft 55 the following 125 mechanism is preferably employed. Attached to sleeve 130 is a cam 63 (Fig. 5) coacting with a roller carried by an arm 64. Integral with arm 64 is an arm 65 which is connected to one arm of a bell crank 67 by a twisted link 66 (see also 130 Fig. 6). The other arm of bell crank 67 is connected to a link 68 carrying a stud 69 (Fig. 4) engaging an annular groove of a sleeve 70 slidably mounted on shaft 46. Also slidably mounted on shaft 46 but secured to sleeve 70 is an arcuate 135 rack member 71 meshing with a pinion 72 attached to a shaft 73. Shaft 73 is journaled in brackets 74 and 75 secured to arm 53 and carries at the other end a similar pinion 76 meshing with a similar arcuate rack member 77 pinned to the shaft 55. Through the train of mechanism just described cam 63 effects the desired shifting movement of shaft 55 to open or close the jaws or gripper arms 58.

In order to effect the desired rocking movement 140 of shaft 55 a cam 78 (Fig. 3) secured to sleeve 130 is provided. This cam coacts with a roller 79 carried by an arm 80 the upper end of the arm being attached to an arm 81 by a link 82. As 145 shown in Fig. 4, arm 81 has a splined connection 150

83 to shaft 55 the arm 81 being confined by bracket extensions 84 of the bracket 75 engaging the sides of a collar 81a which is attached to arm 81. Attached to shaft 55 is an arm 85a (Fig. 3) biased by a spring 86a acting to hold shaft 55 in a position determined by cam 78.

When the parts are in their normal position, as shown in Fig. 3, the jaws 58 firmly grip the plate from which the next printing is to be effected. When the sleeve 130 is driven, cam 50 is almost immediately effective to rock shaft 46 to lower arms 52 and 53 and parts carried thereby until shaft 55 occupies its lowest position, illustrated by dotted lines in Fig. 3. As the parts are thus brought to their lowest positions cam 78 is effective to rock arm 80 and through the train of mechanism previously described rock shaft 55 slightly in a counterclockwise direction. This will result in placing the seized printing plate directly against the record strip 20 at which time a printing impression will be effected by the following mechanism.

Secured to a shaft 85 (Fig. 4) journalled in the side frames 47 is a pair of downwardly extending arms 86 (Fig. 3) integrally connected at their lowermost ends by a cross piece 87 to which is affixed an inked felt pad 88. (See also Fig. 2.) Also secured to shaft 85 is an arm 89 (Fig. 3) connected to a cam operated bell crank 90 by a link 91. The roller 92a carried by one of the arms of the bell crank 90 coacts with a cam 92 secured to sleeve 130. When the plate 26 occupies the proper printing position the high part of the cam 92 is effective to rock the yoke 86-86 and inked pad 88 against the plate and directly over the stenciled name portion to thus produce a like impression 25 on the record sheet 20 which suitably identifies the matter previously printed. When the inked pad 88 has been moved reversely out of the way the cam 50 is then effective to elevate shaft 55 to the uppermost dotted line position, cam 78 being effective during this time to rock the shaft 55 to bring the seized printing plate directly in front of the stacked plates 26 from which printings have already been effected. A continued rocking movement of shaft 55 will force the seized plate behind pairs of latching arms 93, 94 (Figs. 3 and 4) to hold the plate in stacked position. The latching arms are secured to their respective supporting shafts 95, 96 and are urged towards each other by a spring 97 (Fig. 5). In order to accommodate the grippers 58 the side plates 98 of the receiving chute are cut away at 99 as clearly shown in Figs. 1 and 5.

After the plate is in stacked position the cam 63 (Fig. 5) is then effective to separate the grippers 58 which release their hold on the stacked plate 26. At the termination of this cycle of events shaft 46 is restored to its normal position bringing the parts again to the position shown by full lines in Fig. 3, the grippers 58 now being drawn towards each other to receive a new printing plate which is fed to the grippers during the time the grippers are in horizontal alignment with the plate being fed thereto.

As the record cards carrying group classification are sensed by the brushes 15 the perforations are compared with the group classification perforations 27 of the printing plates 26 and if the perforations completely agree further operation of the machine will ensue. Referring to the circuit diagram in Fig. 9 it will be observed that current to the brushes 15 and various relays is supplied by main lines 100 and 101. From main line 100 a wire 102 leads to a metal block 103

carrying brushes 15 each of which continues the circuit connection to an individual segment plate 104 through a perforation in a record card. The circuit then extends by a jumper connection 105 to the relay magnet 106 when a pair of reading levers 107 and 108 are electrically bridged. It will be apparent that the circuit connection just described is duplicated for the different denominational orders and while the diagram shows an embodiment for analyzing only three orders, this number may be altered to coincide with the number of denominational orders of the perforations 27 representing the group classification number of the printing plates 26.

Each relay magnet 106 when energized is 90 adapted to close its relay contacts 109 which are in serial connection with a clutch relay magnet 110 shunted across the main line wires 100 and 101. Brushes 111 and 112 engage the hubs of the reading levers 107 and 108 to provide for a continuous electrical contact during their movements. (See also Fig. 8.)

As shown in Figs. 7 and 8 the metallic hubs to which levers 107 or 108 are secured are mounted upon a tube of insulating material surrounding shaft 115. Brushes 111 or 112 as the case may be contact the associated metallic hub so that electrical contact with the hub is maintained even though the related lever 107 or 108 is rocked about shaft 115.

From Figs. 3, 4, and 7 it will be observed that the levers 108 for the different denominational orders are tied together for synchronous operation by a rod 113 passing through insulated extensions of said levers. Rod 113 is supported at 110 its ends by a pair of arms 114 pinned to a rock shaft 115 which carries another arm 116 (Fig. 1) joined to one arm of a bell crank 117 by a link 117a. The other arm of bell crank lever 117 is connected to the midpoint of an arm 118 by a link 119. The arm 118 carries a roller 120 engaging a profile cam 121 attached to a stub shaft 122. This shaft, by bevel gear connections 123 and 124, is driven from the shaft 21 which, it will be recalled is rotated as an incident to each listing operation. Cam 121 is arranged to rock the rod 113 about shaft 115 (Fig. 3) during each item listing operation so that the levers 108 contact index point plates 125 simultaneous with the sensing of the corresponding index point perforation of the record card by the brushes 15. Index point plates 125 are in the form of curved spring plates which are wide enough to contact companion levers 107 and 108 when their angular positions coincide. Normally, the levers 107 and 108 are displaced with respect to their angular setting by reason of the fact that a spring 126 (Fig. 3) connected to an integral extension of each related lever 107 rocks the same to engage a laterally projecting insulating block 127 attached to the companion lever 108. It will be apparent from Fig. 3 that as rod 113 is rocked, springs 126 will cause levers 107 to follow the movement of levers 108 until one of the levers 107 is arrested by the engagement of a reading lever 140 128 with one of the perforations 27 in the group with which it is in alignment as shown in Fig. 7 and as will be later described in detail. Thereupon lever 107 will be stopped and as lever 108 arrives adjacent an index point plate 125 corresponding to a perforation presented to brush 15, levers 107 and 108 will be electrically bridged by one of the plates 125 thus energizing the related magnet 106 which draws downwardly its armature structure 129 (Fig. 3) to close related con-

150

tacts 109. As each pair of contacts 109 are closed they are latched in such position by a related latching lever 130a and when all of the pairs of contacts 109 are closed the clutch relay magnet 5 110 (Fig. 5) will be energized.

It will be apparent that during the first and succeeding listing operation the reading levers 128 (Fig. 3) will be drawn over the printing plate 26 until each lever 128 engages a perforation 27.

- 10 Due to the formation of the hooked end of the lever 128 the related lever 107 will be stopped in its movement when the lever 128 enters a perforation. (See Fig. 7.) Companion levers 108 continue to contact the remaining contact plates 15 125 of the series but upon the return thereof they pick up and return such levers 107 that have been arrested by the perforations 27, levers 128 being merely cammed out of such perforations to be brought to the normal starting position. The 20 particular plate 26 which is analyzed by reading levers 107—108 constitutes the one fed from the stack during the previous total printing operation, and although the plate is successively analyzed during each item printing or listing operation the clutch relay magnet 110 is energized during the first listing operation if the group classification perforations in the record cards and printing plates agree in all orders. If the printing plate 26 does not correspond to the 25 30 group classification of record cards magnet 110 will not be energized and the machine will be stopped in its operation, as will be described hereinafter.

As previously stated when the group classification of successively fed record cards changes the machine is conditioned for total taking operations and in the event that the classification of the group of cards analyzed is identical to the group number represented by the perforations 40 of the printing plate in analyzing position, clutch magnet 110 will be energized to cause an operative connection between the driven shaft 41 and the cam carrying sleeve 130 (Fig. 4). The bevel gear 42, previously described, is secured to shaft 41 which also has secured thereto a disk 131 (Fig. 5) having a cam notch 132 in its periphery normally engaging a pawl 133 carried by a disk 134 secured to the sleeve 130. A tail of pawl 133 normally underlies a pin 135 carried by an upstanding arm of the armature structure 136 of relay magnet 110.

It will be evident from Fig. 5 that when the pin 135 is in such a position that it is over the tail of pawl 133 and the disk 131 turns clockwise in a total taking operation the cam notch 132 of disk 131 will cause the pawl 133 to be cammed out and thus disengaged from the notch 132 in the disk 131 so that disk 134 and sleeve 130 will not be rotated during such total taking operation. However, if magnet 110 should be energized under the conditions previously stated, the pin 135 will be brought away from over the tail of pawl 133 and since the pawl 133 engages the notch 132 under action of a suitable spring, the turning of the disk 131 in a clockwise direction will cause the disk 134 to be turned since pawl 133 is mounted on the disk 134. The disk 134 and sleeve 130 are therefore driven a complete revolution to perform the functions previously described.

76 Contacts 109 are opened to deenergize magnet 110 after the clutch connections between disks 134 and 131 have been established causing pin 135 to subsequently engage over the tail of pawl 133. Underlying tails of the latching levers 130a

is a bail 137 (Fig. 3) which is connected to a bell crank lever 138 by a link 139. One arm of the bell crank lever 138 is in the plane of a pin 140a secured to a disk attached to shaft 41 so that as the pin 140a contacts the bell crank lever the link will be rocked resulting in rocking the bail 137 and latch levers 130a, the unlatched contact springs 109 opening under their own resiliency thus deenergizing the clutch relay magnet 110.

80 In order to prevent the machine from continuing its operation in the event that a wrong plate is fed, or failure of the feeding of a plate, the present invention contemplates the provision of certain electrically controlled precautionary devices.

85 As more fully disclosed in the Lake Patent No. 1,379,268 the main tabulating motor is provided with an emergency or record controlled stop circuit and preferably included in this circuit are two pairs of serially connected contacts 140 and 141 (Fig. 5). Upon closure of both contacts operation of the tabulating motor may be initiated but upon opening of either pair, operation will be inhibited. The machine also includes a plate 90 operated lever 142 the tail of which is adapted to engage the upper surface of a printing plate or matrix as it is fed, to thereby rock the lever to close contacts 140. A similar plate operated lever 144 is adapted in the same way to close its related contacts 141.

95 It will be observed that lever 142 engages the intermediate plate while lever 144 engages the plate fed first, or stated in other words, at the end of three total printing cycles, there will be one plate seized by grippers 58 and engaged by lever 144, an intermediate plate engaged by lever 142, and the last plate fed, in reading position and co-acting with reading levers 128. To start the tabulator without any printing plates physically contacting with levers 142 and 144 the following 100 mechanism is provided. A pin 142a carried by a lever 145 secured to a shaft 146 is adapted to co-operate with the longer contact plate of contacts 140 and when urged in a counterclockwise direction is adapted to close contacts 140. A similar 110 set of parts comprising a pin 147a carried by a lever 147 secured to a rock shaft 148 is associated with contacts 141. Closure of the contacts is, however, prevented by latching levers 149 and 150 115 engaging the tails of the respective levers 145 and 147, which condition exists after a total taking 120 and 147, which condition exists after a total taking 125 operation.

130 Closure of contacts 140 and 141 by unlatching of the levers 145 and 147 is arranged for when the first printing plate of a stack is manually fed to reading position.

135 In alignment with a pin 151 carried by the arm 32 (Fig. 5) is a shoulder 152 of an externally operable slide 153. When the slide is pushed it results in rocking shaft 33 to accomplish a feeding operation as described heretofore to cause the bottom plate of the stack to be fed to reading position. As the slide is operated pins 154 carried thereby coact with tails of latching levers 149 and 150 respectively, to disengage them from their related levers 145 and 147. Attached to an arm 140 secured to shaft 146 is a link 155 biased by a spring 156 to rock lever 145 to close contacts 140 when the lever 145 is released. Similarly, attached to an arm 145 secured to shaft 148 is a link 157 biased by a spring 158 provided for the purpose of closing contacts 141 associated therewith in a similar manner. It will be obvious therefore, that positioning of the first plate to the reading position 150

will close contacts 140 and 141 to permit operation of the tabulator.

- Summarizing the above, it will be clear that the listing of items represented by the record cards 5 will then ensue, item printing, of course, being performed at the printing line determined by platen 19, and the record strip being spaced an increment each listing operation. Upon a change in group classification the machine will be conditioned for a total printing operation, which will then ensue. If the group classification of both record cards and the analyzed printing plate agree in all orders, relay magnet 110 will be energized, resulting in feeding the second lowest plate from 10 the stack. The plate previously analyzed will then occupy the intermediate position, physically contacting lever 142 to retain contacts 140 closed. After the co-operation of lever 142 with the first plate fed, a pin 160 carried by disk 131 will engage 15 one arm of a bell crank lever 161 connected to link 155 restoring lever 145 to ineffective latched position.

It will be observed that no plate has yet reached lever 144 so that it is ineffective to close contacts 20 141. Secured to shaft 41 is a pinion 162 driving a gear 163 with a two to one ratio, gear 163 carrying a pin 164 adapted to contact, by reason of the gear ratio selected, during the second total printing cycle one arm of a bell crank 165 secured to link 25 157. Therefore, it will be apparent that since pin 164 does not operate arm 165 during the first printing cycle, that lever 147 will not be latched and thus be effective to keep contacts 141 closed, permitting the machine to operate for a second 30 tabulating operation.

The machine is preferably equipped with a paper feeding mechanism that will feed the record strip a definite amount for each account printing operation thus permitting pre-printed work forms 40 to be used and resulting in printing of the identifying data 25 at certain lines on each work sheet. It should also be explained that if the number of 45 items listed does not come up to the predetermined number that may be accommodated on each work sheet the paper strip is supplementally fed after the last item printed to provide for printing the total at a predetermined line, which is generally at the bottom of a sheet. A type of paper feeding mechanism that will provide for the above is 50 shown fully in the co-pending application of F. M. Carroll, Serial No. 287,549, filed June 22, 1928 to which reference may be had for further details of construction and operation.

It will be observed that printing of items and 55 totals takes place at a line distant from the printing line of the identifying matter, requiring several accounts be printed before any account can be identified by printing from its related printing plate. While an account is printed, the related 60 plate is in analyzing position. When the subsequent or second account is printed, the plate related to the preceding account occupies an intermediate position, the first printed account on the record strip 20 then occupying an intermediate 65 position with respect to the printing lines determined by platen 19 and inked pad 88. When the third account is printed the record strip will be advanced sufficiently to permit printing by the related plate which has now been fed to the grippers 70 58 and which is brought to the printing line during the third printing cycle.

It will be recalled that while pin 164 is ineffective to cause the restoration of lever 147 to latched position to permit contacts 141 to open at the 75 termination of first total printing cycle, it is ef-

fective during the subsequent, or second total printing cycle. At this time, however, a plate is in cooperation with the lever 144 causing contacts 141 to be retained in closed position, and, in fact levers 142 and 144 will keep contacts 140 and 141 closed as long as proper plates are fed. In the event that a wrong plate is fed the next operation is prevented directly thereafter. The manner in which this is performed is as follows:

In the event that group classification performances of the printing plate and record cards do not agree clutch magnet 110 will not be energized. The machine will, however, be conditioned for a total taking operation thus driving shaft 41. Pin 160, will therefore relatch arm 145 if it is not already in such position where it is ineffective to keep contacts 140 closed, and since the first plate will remain in analyzing position, lever 142 will not be engaged by a plate to close contacts 140. At the termination of the total taking cycle, operation of the machine will be discontinued until the proper plate is placed in position and tabulating in connection with the group of previously tabulated record cards and proper plate again resumed.

Since pin 140a is carried by a disk attached to shaft 41 it will be effective to restore the series of contacts 109 to open position if they were closed by the agreement of perforations in certain orders, preparatory to being set up in accordance with the plate substituted for the wrong one.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only by the scope of the following claims.

I claim:

1. In a machine in which record cards containing classification perforations are fed in groups of the same classification, means for feeding the record cards, means for feeding members also containing classification perforations and stencilled characters from which characters an impression may be effected, analyzing means for comparing the classification perforations of the first record of a group with the classification perforations of an impression member, means whereby other data may be recorded from the records if an agreement is ascertained, and a supplemental data recording device for effecting an impression from the member upon completion of the recording of the data from the records.

2. The method of identifying data represented by a plurality of classified tabulating cards and printed on a sheet which consists in providing identification impression members with printing characters and differentiating classifications, analyzing and comparing the classifications of an impression member with the classification of the tabulating cards, and effecting a printing impression from the printing characters on the impression member when there is an agreement in classification.

3. A tabulating machine comprising record controlled printing devices for printing upon a record sheet an item represented by the perforations in an automatically fed controlling record, said record also containing classification perforations, a separately fed printing plate having printing characters and also having

- classification perforations, means for analyzing and comparing the classification perforations of the record with those of the printing plate, and means, the operability of which is dependent on 5 the result of the comparison, for effecting a printing impression from the characters on the printing plate.
4. The combination with an impression member containing in columnar arrangement differentiating classification perforations and printing characters, of means comprising a series of analyzing elements only one for each column, means for effecting a relative movement between said member and elements, whereby the 10 element appropriated to a related column senses the perforations therein, and means dependent in operation upon the analysis for effecting an impression upon a record sheet from the characters of said member.
- 20 5. In a machine of the class described the combination with a series of tabulating cards each containing classification perforations, of an impression member having printing characters and classification perforations, tabulating card controlled means for printing items under control of other perforations in the cards, and means controlled by the tabulating cards and said member for causing the impression member to be used to identify the items derived from tabulating cards when the classification of the cards and member agree.
- 30 6. In a machine of the class described controlled by several groups of tabulating cards, means for feeding a group of tabulating cards of the same classification, a printing plate, means for automatically feeding a printing plate for each change in classification of the tabulating cards, tabulating card controlled means for printing items on a sheet, and means for effecting a printing impression from a plate on said sheet to identify data thereon derived under control of the tabulating cards.
- 40 7. In a machine of the class described, tabulating card controlled means whereby data of an account represented by a series of tabulating cards may be derived and printed on a sheet, a plate having printing characters to identify the account data by printing identifying characters on the sheet, said series of tabulating cards and plate containing classification perforations, and means for comparing the classification perforations of only one of the series of like tabulating cards with the classification perforations of said plate to determine whether 50 the identifying data will be printed from said plate.
- 55 8. In a machine controlled by a series of impression members having classification designations, the combination of means for feeding one of the impression members for a printing operation on a record sheet, printing devices controlled by record cards containing classification designations, and means for separately analyzing the classification designations of one of the record cards and said impression member and comparing the analysis to determine whether the impression member analyzed will be fed for a printing operation.
- 60 9. A machine of the class described comprising means for effecting the printing of a classified item upon a record sheet, an identification impression member having classification designations, means for analyzing the classification designations of said member to determine whether or 70 not a single imprint is to be effected from said member, means for feeding said member to the analyzing means, means for feeding the member to the record sheet for a single printing operation, means for effecting only a single printing operation from said member, and means whereby the operation of the last named feeding means and the last named printing means is dependent upon the analysis of the designations.
- 75 10. In a tabulating machine, means for feeding tabulating cards in a group of the same classification, means to print data under control of said cards, a printing plate containing classification perforations, means for feeding said printing plate for a printing operation to identify the printed data derived from the group of tabulating cards when the classification of the plate and cards agree, and means for stopping the operation of the tabulating machine by failure of the feeding of said plate when a disagreement is obtained.
- 80 11. A machine of the class described comprising an impression member containing classification perforations in a plurality of orders, a tabulating card having classification perforations in corresponding orders, means for comparing the classifications by analyzing the tabulating card in motion and a member at rest, and a printing device for obtaining a printing impression from the member only when an agreement in all orders of both the member and card is reached.
- 85 12. In a machine of the class described, printing means under control of several groups of perforated records for effecting the recording of groups of data, said records having classification perforations demarcating the several groups, means for feeding an impression member having classification perforations for each group of records, an analyzing mechanism for analyzing the perforations of an impression member, an analyzing mechanism for analyzing the classification perforations of a record of a group, and devices for taking an impression from the member if the analysis determines an agreement in perforations.
- 90 13. A machine of the class described comprising a mechanism for printing a group of items of the same class upon a record sheet, a printing plate separately fed from a stack for printing a line of characters on the sheet, an operating means effective upon completion of the printing of said group of items of the same class, and means controlled thereby for effecting a printing impression from said printing plate upon the record sheet to identify the printed items thereon.
- 95 14. A machine of the class described comprising controlling means for controlling the printing upon a record sheet of a group of items, a classified identification impression plate fed for printing upon the record sheet after completion of the printing of said group of items, and means under control of the printing controlling means and said identification plate for causing the printing plate to be used for a printing operation when it identifies items of the same class.
- 100 15. In a machine of the class described controlled by groups of records having classification indications, means under control of a group of records for controlling the printing upon a strip of a group of items of the same classification, a member from which a printing impression may be effected to identify said items, said member carrying classification indications, means for comparing the classification of the records and said member, and means effective when the classification of the records and said member are in
- 105 110 115 120 125 130 135 140 145 150

- agreement for effecting a printing impression from said member upon said strip.
16. A machine of the class described comprising means for printing a group of classified items upon a record sheet, means for automatically feeding an impression member from which a printing impression may be effected upon the record sheet to identify the group of items, said impression member having classification designations, means for analyzing the designations of said member, and means dependent in operation upon the analysis for effecting a printing impression upon the sheet from said impression member.
- 15 17. A machine of the class described comprising printing means under control of designations of a series of record cards for effecting the printing of items upon a record sheet, said record cards having classification designations, means for feeding an identification impression member having classification designations, and means for comparing the classification designation of one record card or a series of similarly classified record cards with the classification designations of the impression member.
- 25 18. In a tabulating machine, means for manually feeding the first impression member of a series and thereafter one automatically between groups of tabulating cards, printing means under control of perforations of each of a group of tabulating cards for printing items, means for comparing the classification designations of a member with those of the related group of tabulating cards, and means, the operation of which is dependent upon the result of the comparison, for effecting a printing impression from the member.
- 30 19. In a tabulating machine, means for printing an item under control of perforations of a tabulating card, means for feeding an impression member, means for effecting an imprint from said impression member, and means for comparing the classification designations of the member with those of the card to cause the operation of said printing means and automatic operation of the feeding means to present a subsequent impression member for correlation with a subsequent tabulating card or cards.
- 35 20. In a tabulating machine, means adapted to be manually operated to feed an impression member for an analyzing operation, means effective after the feeding operation of the impression member to cause the tabulation of one or more tabulating cards, means for comparing the classification designations of the impression member fed with those of the tabulating card to cause an automatic operation of the feeding means and to cause a printing impression from said member upon an agreement in classification designations, and means whereby the comparing means upon location of a disagreement in the classification designations causes subsequent stoppage of the operation of the machine by fail-
- ure of the automatic operation of the feeding means.
21. In a tabulating machine, means for sequentially feeding a series of impression members, one between each change in classification of tabulating cards, means for printing items under control of the cards and for taking an impression from an impression member to identify the correlated items, and comparing means for comparing the classification designations of each member directly with those of the related tabulating card.
22. In a tabulating machine, means for analyzing value representing designations of each of a series of tabulating cards having classification designations, printing means under control of the cards for printing items, means for automatically feeding impression members having classification designations, means for effecting an impression from one of said members to identify items, means effective upon location of a change in classification of tabulating cards to cause an automatic operation of the feeding means dependent upon the result of the comparison of the classification designations of an impression member with a tabulating card, and means for comparing the classification designations of an impression member with those of a tabulating card to control the automatic operation of the feeding means.
- 25 23. In a tabulating machine, tabulating card controlled means for printing items, means adapted to be operated manually to cause feeding of an item identifying impression member to classification analyzing position and operation of the tabulating card controlled printing means, means for automatically continuing the printing of items as long as successive tabulating cards agree in their classification and effecting an automatic operation of the feeding means upon a change in classification, means for preventing an automatic operation of the feeding means upon a disagreement in the classification of an impression member and a tabulating card, and means whereby the failure to feed an impression member causes the stoppage of the tabulating card controlled item printing means.
- 30 24. In a tabulating machine, means for feeding a classified impression member to analyzing position, means for causing the tabulating of items represented by classified tabulating cards, means for effecting a printing impression from said member, and intercontrolling means between said member and the tabulating cards whereby a change in classification of the latter and an agreement in the classification of the card and said member causes an operation of the feeding means and a disagreement in the classification of the impression member and a tabulating card prevents the operation of the printing means and feeding means.

FRED M. CARROLL.
